Primary Examiner — Mitchell I. Siegel*(74) Attorney, Agent, or Firm* — John K. Park; PARK LAW FIRM(57) **CLAIM**

The ornamental design for a golf mat, as shown and described.

DESCRIPTION

FIG. 1 is a perspective view of the golf mat;
FIG. 2 is a top plan view thereof;
FIG. 3 is a right side view thereof;
FIG. 4 is a left side view thereof;
FIG. 5 is a front view thereof; and,
FIG. 6 is a rear view thereof.

The broken lines in the drawings depict environmental subject matter of the golf mat only and form no part of the claimed design.
